SHEET METAL CONTAINER

Augustus L. Merolle, Brooklyn, N. Y., assignor to
 Empire Metal Cap Co. Inc., Brooklyn, N. Y., a
 corporation of New York

Application October 11, 1938, Serial No. 234,343

6 Claims. (Cl. 220—10)

This invention relates to containers and receptacles, and in particular to a type of container which is used for keeping moist substances and maintaining them in their original state for a considerable length of time, so as to prevent them from losing their moisture contents too quickly.

Moist substances, such as paste, cold cream and the like are most generally kept in jars of porcelain or similar material. Since however these jars are fragile as well as heavy, causing breakage and high expenses in cost of shipment, and since moreover such jars are objectionable because their surfaces will not permit lithographic treatments, wherewith to enhance the graceful appearance by ornamental design on the face of the jar, the tendency to introduce metal containers in place of jars, has therefore made considerable headway.

Metal containers which are to possess the heat insulating characteristics of porcelain jars and the like are required to have a protective shell or housing surrounding the receptacle and which housing is to be spaced or set off from the wall of the receptacle, so that the air between the latter and the housing may serve as an insulator against changes in temperature.

While containers of this type are sufficiently known to the art, they nevertheless disclose characteristics which still require further improvements concerning their appearance and especially their process of manufacture.

It is therefore one of the objects of my invention to produce a container of sheet metal of the type described which is built of as few parts as possible; which is simple to manufacture and which is without unsightly seams, ridges and the like.

A further object of this invention is to produce a container having the inner vessel or receptacle and the surrounding cap-retaining wall section or housing formed from one sheet of metal.

Another object is to produce this one piece double-walled container by a novel method, wherewith the inner receptacle is pressed out of a former extension of the outer wall section, to be described hereafter.

A further object is to produce on the edge portion of a shortened outer wall section, novel formations adapted for fastening thereto an outer shell or closure element for the purpose of insulating the inner vessel from the outside.

A still further object of the invention is to provide a novel metal cap for the container and which cap has a double wall and is rigid in construction.

Other and ancillary objects of the invention will appear hereinafter.

In the accompanying drawing which illustrates the invention—

5 Fig. 1 is a central sectional view of a container and its cap;

Fig. 2 illustrates a sheet metal container, which slightly differs in form from that shown in Fig. 1;

10 Fig. 3 shows a part of a container like Fig. 1 but with a modification in the joint of the outer shell, the joint being in an incomplete stage;

Fig. 3A is a fragmentary view showing the joint in completed condition;

15 Fig. 4, which is similar to Fig. 3, shows a different formation of this joint in an incomplete stage;

Fig. 4A is a fragmentary view showing the joint completed;

20 Fig. 5 shows a modified construction whereby the outer shell is secured to the edge of the outer wall section;

Fig. 6 illustrates a full outline of a container similar to Fig. 2, but in which the bottom of the outer casing is not integral with the outer shell;

25 Figs. 7 to 11 show a series of developments which illustrate a novel method of producing from one sheet of metal a receptacle surrounded by a depending outer wall section;

Fig. 12 shows a central section of a container having a modified construction in which the lower edge of the depending wall section integral with the inner receptacle engages frictionally with the cylindrical edge of an outer shell or casing;

30 Fig. 13 shows in outline a partial view of Fig. 12 and in which the threaded wall section is not integral with the inner shell or vessel but is secured thereto;

Fig. 14 and 15 show each a modification of the outlines illustrated in either Fig. 3 or Fig. 4.

Referring to Fig. 1, the structure shown therein comprises a container to which is applied a cap. The structure is circular in plan view and the container comprises an inner receptacle having a circular cylindrical wall 1 with which is integrally formed the bottom 2. Integrally formed and joined to at the top of the side wall 1 is a reflexed portion 3 bent back about and spaced from the cylindrical wall 1. In this reflexed portion may be formed the screw-threads as shown adapted to engage with a screw-threaded closure or cap.

The extremity of the portion 3 has a flat portion 4 which at its edge is turned up for engagement with the curled-over upper edge of the

outer cylindrical shell or casing 5. The integral portion comprising the cylindrical wall 1, bottom 2 and the reflexed portion 3 is formed of sheet metal. This curling of the edge is such as to make a tight and secure fastening. The cylindrical shell 5 is of sheet metal, is spaced from the vertical receptacle wall 1. The bottom 6 of the outer casing is of sheet metal and is fitted within the circular wall 5 and secured therein by intercurling the edges of the bottom plate 6 with the lower edge of the cylindrical wall 5.

In thus curling the edges of the bottom 6 and wall 5 together, the bottom 6 is liable to back off or slide upwardly in the casing 5. To prevent this a plate or block 7, of suitable material, preferably light, such as wood or corrugated board, is inserted, and this, coming against the bottom of the inner receptacle, prevents the backing off of the bottom plate 6 during the operation of curling it to the lower edge of the casing 5. This plate 7 may remain in the completed article.

The cap, formed of sheet metal and circular in plan, may have the top wall 8 with the depending marginal skirt 9. This skirt, at its lower edge, is bent inwardly and upwardly to form an inner wall 10 spaced from the skirt 9, and having an upwardly turned flange 11 at its upper edge which serves to stiffen and support the inner wall.

In the inner wall 10 is formed a screw-thread adapted to cooperate with the screw-threads in the reflexed portion 3 of the container. Between the upper end of the inner receptacle 1 and the top wall 8 of the closure is a liner 12, of suitable resilient material as is well known, which liner is compressed between the upper end of the inner receptacle of the container and the top wall of the cap or closure when the latter is screwed home upon the container so as to form a tight seal about the top of the container. The upper edge of the container is formed with a narrow ridge 13 upon which the liner rests and facilitates the making of a tight seal about the top of the receptacle by the liner. The external diameter of the cap skirt 9 is preferably approximately the same as the diameter of the outer casing 5 so that the side walls of the structure, including the cap and container, will be substantially in a straight line. The cap can be screwed on and off of the container in a manner as is well understood.

In Figs. 7 to 11 inclusive is shown the various stages of a method for forming the portion of the container comprising the parts 1, 2 and 3. Starting with the relatively shallow, wide and rimmed cupped member 14, such circular sheet metal article is drawn into the structure of Fig. 8 wherein it will be seen that the structure has been lengthened and reduced in diameter, and provided with a shoulder 15 separating the two cylindrical portions 16 and 17 of different diameters, the portion 17 having the flat flange 18. The article as shown in Fig. 8 is then subjected to an operation whereby it assumes the form as shown in Fig. 9, the rounded shoulder 15 being formed into the two abrupt shoulders 19 and 20. Also the bottom 21 and the lower portion 22 of the wall 16 are forced inwardly within the upper portion of the wall 16 so that the bottom 21 is substantially in alignment with the shoulder 20. This leaves the space within the cylindrical portion 17 empty so that a threading tool may be inserted therein.

A thread 23 is then formed in the cylindrical part 17 so that the article is in the form as shown in Fig. 10. The shoulder 19 provides sufficient space for the forming of the threads, and the shoulder 20 forms a rest for a support to hold the portion 17 with its thread 23 in position when the bottom 21 and part 22 are forced further inwardly into the form as shown in Fig. 11. Also in this last operation the flange 18 has its edge turned at substantially right angles as shown in Fig. 11.

The outer circular, cylindrical casing wall 5 is at first formed with straight sides and may be circumferentially continuous or be formed of a flat piece of sheet metal bent into a circular form and secured together by a longitudinal seam.

The part as shown in Fig. 11 is then placed within the cylinder 5 and the upper edges of the cylinder bent about the edges of the part 3 as described. The bottom 6 having a straight marginal flange or skirt at substantially right angles to the plane of the bottom and which substantially fits within the cylinder 5 is telescoped within the cylinder, there being placed within the cylinder head of the bottom the supporting piece 7 which bears against the bottom 2 of the inner receptacle, the bottom 6 being then brought against the piece 7. The edges of the bottom 6 are then intercurled with the lower marginal edge of the cylinder 5 into fixed and secure relation. The support 7 serving to prevent the bottom 6 from backing off during the curling operation and also this support 7 may operate to support the inner receptacle in addition to the support afforded by the curling of the upper edge of the cylinder 5 about the flange of the part 4.

Referring to Fig. 2 there is therein shown the interior sheet metal member 24 having the integral bottom 25 and having integrally joined to it at its top the reflexed portion 26 bent backwardly along the receptacle 24 and spaced therefrom. Screw threads may be provided in the member 26 for engagement by the screw-threads of a closure or cap. The marginal edge of the member 26 extends outwardly and is intercurled with the upper marginal edge of the circular side wall 27 of the outer casing, which side wall is integral with the bottom 28 of the outer casing, such bottom having, if desired, an inwardly concave portion 29.

At the base of the threads upon the member 26 is formed a shoulder 30 against which the seam formed by the intercurling portions referred to is in more or less tightly close relationship.

It is contemplated that all of the containers referred to in this application will be sprayed or covered with an enamel or paint, and when this is applied to the structure of Fig. 2 any crack or groove which might exist between the shoulder 30 and curled-over portions of the seam joining the reflexed portion 26 with the outer casing wall 27 will be completely filled or smoothed over by the lacquer, enamel or paint so that no appreciable break in the exposed surface will appear.

In the construction of Fig. 2, the bottom of the outer casing being integral with the side wall thereof, there is no problem of securing the bottom in place nor any necessity for any support between the bottom of the interior receptacle and the bottom of the outer casing.

Referring to Figs. 3 and 3A, the inner receptacle of sheet metal and of circular cross section comprising the cylindrical wall 31 integrally

formed with the bottom 32 is integrally connected at its upper edge with the reflexed portion 33 carrying threads adapted to cooperate with threads upon a closure. The marginal edge of the portion 33 is bent outwardly and is provided at its free edge with a curled wire edge or bead 34. The outer casing which is spaced from the inner receptacle is of sheet metal and comprises the cylindrical side wall 35 integrally joined with the bottom 36 which is spaced from the bottom 32 of the inner receptacle, and at its upper end is provided with a circumferential groove 37 above which is the straight cylindrical portion 38. The inner receptacle and reflexed member 33 may be telescoped within the cylindrical portion 38 and snapped into the groove 37 as shown in Fig. 3. The cylindrical portion 38 may then be curled inwardly about the bead 34 so as to tightly grip the same and securely fasten the member 33 and the wall 35 together. In this construction the engagement of the bead 34 in the groove 37 holds the bead against backing off while the portion 38 is being curled about the bead into securing position.

Referring to Figs. 4 and 4A, the structure is similar to that shown in Figs. 3 and 3A. In the structure of Figs. 4 and 4A, however, the bead 39 on the reflexed member secured to the inner receptacle has formed between it and the screw-threads the shoulder 40, and the cylindrical portion 41, which is above the circumferential groove 42 in the side wall of the upper casing, is somewhat longer than in the structure of Figs. 3 and 3A, and the securing of the parts together is accomplished by the bending of the cylindrical portion 41 into a horizontal position as shown at 43 in Fig. 4A where it lies against the shoulder 40 and so reduces any clearances forming cracks or grooves between adjacent parts, the edge of the part 43 being entirely glossed or smoothed over by the application of the enamel, lacquer or paint as already referred to.

Referring to Fig. 5, the construction is similar to that of Figs. 4 and 4A except that the cylindrical straight part 41 is made shorter, somewhat the same as the part 38 of Figs. 3 and 3A and is curled downwardly into the curled edge of the reflexed member secured to the inner receptacle. This forms a structure with very small interstices or cracks between members, such as are formed being fully filled up and smoothed over by the applied lacquer, paint or enamel as referred to.

Referring to Fig. 6, the construction comprises the circular, cylindrical sheet metal inner receptacle having the side wall 44 with which is integrally formed the bottom 45. Integrally connected to the upper edge of the wall 44 is the reflexed portion 46 having threads for engagement with a closure and having an outwardly turned portion 47 intercurled with the upper edge of the circular, cylindrical side wall 48 of sheet metal spaced from the wall 44 and forming, with the circular sheet metal bottom 49, the outer casing of the container. The wall 48 may be formed of a flat sheet of metal bent into a circle and have its edges secured together as at 50, or it may be circumferentially continuous.

The edges of the bottom 49 are intercurled with the lower marginal edges of the wall 48 and is provided with a concaved portion 51 which bears against the bottom 45 of the inner receptacle. Inasmuch as the bottom of the outer casing bears against the inner receptacle it will be

held thereby from backing off during the curling operation which secures it to the wall 48.

Referring to Fig. 12, the container is formed of sheet metal and comprises the inner receptacle having the cylindrical side wall 52 integral with the bottom 53. Integrally secured to the top of the side wall 52 is the reflexed portion spaced from the wall 52 and comprising the portion 54 threaded for engagement with a threaded closure cap, a circumferential rib 55 at the base of the threaded portion and an inwardly offset cylindrical portion 56. The outer casing comprising the cylindrical side wall 57 integral with the bottom 58 and at the upper edge of the wall 57 has the inturned elongated bead 59. The cylindrical portion 56 fits with a tight frictional fit within the inner side of the circumferential bead 59 so that the inner receptacle and outer casing may be assembled by pushing the cylindrical portion 56 within the bead 59 until the rib 55 rests upon the top of the bead 59, and may be disassembled by pulling the cylindrical part 56 out of the bead.

It will be noted that the outermost portion of the rib 55 is substantially in line with the outer circumference of the wall 57, and when the closure cap is in position upon the container its outermost circumference will also be in substantial alignment with the wall 57. This produces the effect of a container with substantially straight vertical walls but with the rib 55 exposed to observation from the exterior when it may be made of a color contrasting with adjacent portions for purposes of decoration, as an indication of the contents or for other reasons.

Fig. 13 shows a container the same as Fig. 12 except that instead of the reflexed portion comprising the threaded part 60, the rib 61 and the inwardly off-set cylindrical portion 62 being integrally connected with the side wall 63 of the inner receptacle, such side wall is made separate from and secured to the reflexed portion by the inter-curled edges at 64 of the side wall 63 and reflexed portion.

Referring to Fig. 14 the sheet metal structure therein shown comprises an inner receptacle having the cylindrical side wall 101 integrally joined to the bottom 102 at its bottom and at its top integrally joined with a reflexed portion comprising the part 103 having screw threads for cooperation with corresponding screw threads upon a closure cap, the outwardly projecting rib 104 at the base of the threaded part 103 and a cylindrical inwardly offset part 105 projecting downwardly from the rib 104. The outer casing comprises a cylindrical side wall 106, the lower edge of which is integrally joined with the bottom 107 which has an indented or concaved central portion upon which the bottom 102 of the inner receptacle rests. Near the upper edge of the outer wall 106 is an inwardly projecting rib 108 which closely fits about the cylindrical part 105. Above this rib the upper edge of the outer casing is curled tightly about the rib 103 at 109 securely assembling together the inner receptacle, the reflexed portion and the outer casing. It will be apparent that this structure may be readily and inexpensively made.

The outer casing is first made with the part 109 cylindrical and substantially in line with the wall 106. The inner receptacle with the reflexed portion are then entered within the outer casing, the part 105 closely fitting the rib 108, the inward movement being limited by the rib 104 coming against the rib 108. The parts being

firmly held in this position, the part 109 is curled tightly about the rib 103 when a strong and secure structure is formed. It will be observed that although the bottom 102 comes against the bottom 107 they might be spaced apart, the inner receptacle then being supported by the rib 109 resting upon the rib 108.

It will be observed that the portion 109 curled about the rib 104 is substantially in line with the side wall 106 and that it extends to some extent outside the line of the screw threads so that when the closure cap is applied the side wall of the cap may be substantially in line with the side wall 106.

Referring to Fig. 15 there is therein shown a relationship of the inner receptacle 110 and its reflected portion including the screw-threaded part 111 except that instead of having a rib 104 and a cylindrical portion 105 below it as in Fig. 14, the construction in Fig. 15 has the reflexed portion terminating in a bead 112 at its edge, which bead rests upon the inwardly projecting rib 113 in the side wall 114 of the outer casing and the parts are secured in assembled relation by curling the portion 115 above the rib 113, about the bead or wire edge 112.

It will be understood that while screw threads have been shown as the means for securing the closure cap upon the container, it is often that a closure is secured upon a container by simply telescoping its side walls upon a closely fitting neck on the container, the closure cap being held from removal by friction of the parts. The cap engaging neck of the container may be either cylindrical or it may be tapered when the further the lid is pushed on to the container the tighter it will be wedged thereon as is well known.

While the invention has been illustrated in what are considered its best applications it may have other embodiments without departing from its spirit and is not therefore limited to the structures shown in the drawing.

What I claim is:

1. A container comprising in combination a receptacle comprising a vessel surrounded by a wall set off from and secured to said vessel, said wall having a closure-engaging portion and a lateral projection below said closure-engaging portion and an outer casing surrounding and spaced from said vessel, said casing having its upper marginal portion curled about said projection, said casing having a circumferential groove adjacent and below its said curled upper marginal portion, said groove forming a shoulder on which said lateral projection rests.

2. A container comprising in combination a receptacle comprising a vessel surrounded by a wall set off from and secured to said vessel, said wall having a closure-engaging portion and a lat-

eral projection below said closure-engaging portion and an outer casing surrounding and spaced from said vessel, said casing having its upper marginal portion curled about said projection, said vessel and casing having bottoms spaced from each other, said casing having a circumferential groove adjacent and below its said curled upper marginal portion, said groove forming a shoulder on which said lateral projection rests.

3. A container comprising in combination a receptacle comprising a vessel surrounded by a wall set off from and secured to said vessel, said wall having a closure-engaging portion and a lateral projection below said closure-engaging portion and an outer casing surrounding and spaced from said vessel, said casing having its upper marginal portion curled about said projection, said casing having a bottom and side wall integral with each other, said casing having a circumferential groove adjacent and below its said curled upper marginal portion, said groove forming a shoulder on which said lateral projection rests.

15 4. A container comprising in combination a receptacle comprising a vessel surrounded by a wall set off from and secured to said vessel, said wall having a closure-engaging portion and a lateral projection below said closure-engaging portion and an outer casing surrounding and spaced from said vessel, said casing having its upper marginal portion curled about said projection, said casing having a circumferential groove adjacent and below its said curled upper marginal portion, said groove forming a shoulder on which said lateral projection rests.

20 5. A container comprising in combination a receptacle comprising a vessel surrounded by a wall set off from and secured to said vessel, said wall having a closure-engaging portion and a lateral projection below said closure-engaging portion and an outer casing surrounding and spaced from said vessel, said casing having an inwardly extending circumferential projection and said lateral projection upon said wall resting upon the outer side of said inwardly extending projection on said casing.

30 6. A container comprising in combination a receptacle comprising a vessel surrounded by a wall set off from and integral with said vessel, said wall having a closure-engaging portion and a lateral projection below said closure-engaging portion and an outer casing surrounding and spaced from said vessel, said casing having an inwardly extending circumferential projection and said lateral projection upon said wall resting upon the outer side of said inwardly extending projection on said casing.

35 7. A container comprising in combination a receptacle comprising a vessel surrounded by a wall set off from and secured to said vessel, said wall having a closure-engaging portion and a lateral projection below said closure-engaging portion and an outer casing surrounding and spaced from said vessel, said casing having an inwardly extending circumferential projection and said lateral projection upon said wall resting upon the outer side of said inwardly extending projection on said casing, the said lateral projection on said wall being a bead formed by curling the marginal portion of said wall outwardly.

AUGUSTUS L. MEROLLE.
